UNITED STATES PATENT OFFICE.

HENRY L. DE ZENG, OF MAPLE SHADE, NEW JERSEY.

OPHTHALMOLOGICAL INSTRUMENT.

1,158,187.

Specification of Letters Patent.

Patented Oct. 26, 1915.

Original application filed January 11, 1915, Serial No. 1,562. Divided and this application filed February 23, 1915. Serial No. 9,903.

To all whom it may concern:

Be it known that I, HENRY L. DE ZENG, a citizen of the United States, residing at Maple Shade, county of Burlington, State of New Jersey, have invented a new and useful Ophthalmological Instrument, of which the following is a specification.

This application is a division of the application for Letters Patent No. 1562, filed 10 by me January 11, 1915, for an optical instrument.

My invention relates to a new and useful ophthalmological instrument and consists in providing a plurality of reflectors suitably arranged for directing the light from the objective lens to the eye piece with means for increasing or decreasing the focal range and the power of the instrument.

It further consists of other novel features 20 of construction, all as will be hereinafter fully set forth.

It will be understood that my invention is adapted for use with any ophthalmological instrument wherein different focal 25 ranges are necessary or desired, so that the same is equally adapted for such instruments as an ophthalmoscope, binoculars, range finders, telescopes, optometers, or other similar instruments. In the drawings, I have shown the same as particularly applied to an ophthalmoscope and I have shown a construction of one form of a binocular, but it will be evident that, as above stated, the invention is adapted to 30 other instruments and that the arrangement of the parts may be varied, other instrumentalities may be employed, and changes may be made in the construction, which will come within the spirit of my invention, and 35 I do not, therefore, desire to be limited to the exact construction herein shown and described.

Figure 1 is a partial elevation, partial vertical sectional view of an ophthalmoscope or optometer embodying my invention. Fig. 2 is a rear elevation of a portion of the ophthalmoscope on a smaller scale. Fig. 3 is an elevation of a portion of the casing with one plate removed. Fig. 4 is 45 a sectional view on line $x-x$ Fig. 3. Fig. 5 is a sectional view on line $y-y$ Fig. 3. Fig. 6 is a sectional view of a portion of the device in detached position. Fig. 7 is a diagrammatic view, showing the passage of 50 the light from one reflector to the other. Fig. 8 is an elevation on a reduced scale, showing the invention in the form of a binocular. Fig. 9 represents a side elevation of a prism or reflector which may be employed.

60 Similar numerals of reference indicate corresponding parts in the figures.

Referring to the drawings, 1 designates the casing of any suitable form or construction, forming the body portion or the support for the operating mechanism, and which is adapted, when applied to an ophthalmoscope, to be connected with the tube 2 thereof, which latter is adapted to be mounted upon the handle 3, which carries a source 70 of light 4, such as an electric lamp, the said tube 2 carrying a lens 5. In the rear face of the casing 1 and at a suitable point therein, I provide a sight opening 6, which may or may not be provided with a lens or eye 75 piece, and, as here shown, the said sight opening 6 is located adjacent the upper portion of the casing 1 and at one side of the center thereof.

7 designates a reflector of any suitable 80 construction, here shown as a prism, which is suitably mounted in the casing with respect to the sight opening 6 in order to direct light thereto.

8 designates an objective lens suitably 85 mounted upon the side of the casing 1 opposite to that of the sight opening 6 and preferably out of alignment therewith, and, as here shown, the said lens 8 is located adjacent the upper portion of the casing at 90 one side of the center thereof.

9 designates a reflector, here shown as a prism, suitably mounted within the casing with respect to the objective lens 8, in order to receive the light therefrom and to direct 95 the same in a suitable manner.

10 designates a third reflector, here shown as a double reflecting prism, which is suitably positioned within the casing in order to receive the light from the reflector 9 and to 100 direct the same to the reflector 7, whereby it will be understood that the light from the objective lens 8 will be in a suitable and proper manner directed by the reflectors to the sight opening 6 or eye-piece of the instrument.

As will be understood more particularly from the diagrammatic view of Fig. 7, the reflector 9 will direct the central incident ray at right angles to the central incident 110

ray from the object, while the reflector 10 will direct the light first at right angles with its central incident ray and then parallel with its primary incident ray to the reflector 7 which will direct its central incident ray at right angles therewith to the sight opening 6 or eye-piece of the instrument. Suitable means is provided for increasing or decreasing the focal range of the instrument 10 by increasing or decreasing the distance over which the light will travel in passing from the objective lens to the eye-piece, and, as here shown, I have mounted the double reflector 10 in a suitable support 11, which is 15 adjustable or movably mounted within the casing 1 in any suitable or desired manner, and has a pointer or indicating mechanism 12 connected therewith, here shown as extending through the slot 13 in a wall of the 20 casing 1, to be suitably positioned with respect to a series of indications 14, in order that an indication may be had of the adjustment made of the focusing of the instrument upon objects at various distances. From the 25 above, it will be understood that the said reflector 10 is movably mounted with respect to the other two reflectors, in order that by moving the same toward or away from the said reflectors 7 and 9, the distance over 30 which the light will travel in its transit or passage from the objective through the instrument to the eye-piece, will be increased or decreased, thus adjusting the focal range of the instrument, it being understood, however, 35 that any suitable means for accomplishing this adjustment, may be employed.

In order to focus or increase or decrease the magnifying powers of the instrument, when used as an ophthalmoscope or otherwise, 40 I mount a disk 15 in suitable relation with respect to the sight opening 6, in which disk are mounted a suitable number of lenses 16, of different power, and whereby said lenses may be successively brought into alinement 45 with said sight opening, as will be evident. When the instrument is used as an eye testing device, it may be provided with an objective lens and an ocular lens of substantially the same power, and for this purpose 50 one of the ocular lenses of the disk 15 may be employed or the ocular lens may be mounted at the sight opening, as previously stated. Any suitable means may be employed for yieldingly holding the desired 55 lens in operative position. When employed as an ophthalmoscope, I provide a reflecting device, such as a mirror 17, suitably mounted or carried upon the casing 1 in proper position to receive the light from the light source 60 4 and direct the same to the object. Any suitable form of reflecting device may be employed, and as here shown, I have provided a construction, wherein the reflecting device is provided with the two reflecting 65 surfaces 18 and 19 offset with respect to each

other in order to provide the sight opening 20, through which the object may be viewed.

In the operation of the device as an ophthalmoscope, it will be understood that the operator places his eye in line with the sight opening 6 and with the reflecting device 17 directing the light upon the object. The light therefrom will pass through the opening 20 to the objective lens 8 to the reflector 9, will pass downwardly to one face of the reflector 10, from which it will be directed to the other face of the reflector 10, thence upwardly to the reflector 7, and thence to the eye-piece or opening 6. By moving the reflector 10 to the proper place, the instrument is focused or correctly adjusted, as will be evident.

In the construction shown in Fig. 8, I have shown two casings 1, formed in a similar manner to that just described, and adjustably connected by a bar 21 and a set screw 22. By turning the latter, the casings may be moved toward or away from each other, in the direction indicated by the arrows in Fig. 8, to properly locate the sight opening with respect to the eyes of the operator, after which the set screws may be tightened to hold the casing in proper position. In this construction, the reflectors 10 of each casing may be suitably connected by means of a rod 23 which has suitable connection therewith, in order to allow for the adjustment of the casings 1, and which rod 23 is in threaded engagement with an adjusting screw 24, whereby the adjustment of the said reflectors 10 is accomplished.

In Fig. 9 I have shown a form of prism which may be employed, if desired, wherein instead of mounting the lens 8 as shown in Fig. 1, independent of the prism or reflector, a lens 25 is carried thereupon and may be located upon either face of the prism, if desired, but in either case, the operation and effect will be substantially the same since the objective 8 may be positioned, so that the light will pass it before reaching the reflector 9 or after being reflected therefrom.

From the foregoing description, it will be understood that when this instrument is used as an optometer or eye testing device, any adjustment of the reflector or light directing means 10 from normal position, as at zero, will indicate an error in the refraction of the eye under examination, as well as its character, and the scale 14 and pointer 12 are employed for the purpose of indicating the nature and strength of the lens required for the correction of the existing refractive error in the eye under examination. The scale 14 is graduated in ophthalmic lens or dioptric measurements, and will therefore indicate any lens equivalent which may be necessary for the correction of errors of refraction in the eye under examination. It will also be seen from the foregoing descrip- 125

tion that the instrument is provided with an objective lens and an eye lens of substantially the same focal power, and that in consequence thereof, the object when viewed 5 through the instrument will not be amplified. The visual acuity may therefore be correctly determined by means of the instrument. It will be seen also that the construction of the instrument is such as to erect the 10 image and that any spherical lens equivalent required for the correction of errors in the refraction of the eye may be quickly and easily determined at the eye piece through the adjustment of the movable reflector 15 and the coöperation therewith of the pointer and scale. It will also be seen that in this 20 form of optometer neither the eye-piece nor the objective are necessarily adjusted for the purpose of determining the refraction of the eye under examination, and in addition to the image being erected, by reason of the novel construction of the instrument, a 25 positive eye piece may be employed and a large and well illuminated field obtained thereby.

From the above, it will be understood that I have devised a new and useful optical instrument embodying an objective lens and an alternate eye-piece, and a plurality of reflectors, with means for increasing or decreasing the focal range and the magnifying power of the instrument. In the construction illustrated, I have mounted the 30 objective lens and eye-piece in suitable relation to each other, and have provided means adapted to direct the light from one lens to the other in a manner which erects the image and gives an upright position to the object when viewed through the instrument.

Having thus described my invention, what I claim as new and desire to secure by Letters Patent, is:—

1. In an ophthalmological instrument, an 45 objective lens, a reflector coöperating therewith, an eye lens, a reflector coöperating therewith, a third reflector coöperating with the first and second mentioned reflectors, means for increasing or decreasing the 50 distance which the light will travel in passing from the objective lens to the eye lens, and means for indicating the increase or decrease of light travel in ophthalmic lens values.

55 2. In an ophthalmological instrument, an objective lens, a reflector suitably positioned with respect thereto, an ocular lens of substantially the same focal power as said objective lens, a reflector suitably positioned 60 with respect thereto, and a third reflector suitably positioned to reflect the light from the first-mentioned reflector to the second-mentioned reflector and movably mounted to increase or decrease the distance the light 65 will travel in passing from the objective to

the ocular lens, and means for indicating the increase or decrease of light travel in ophthalmic lens values.

3. In an ophthalmological instrument, the combination of an objective lens and an eye 70 piece of substantially the same focal power as said objective lens, whereby the object when viewed through the said lens and eye-piece will appear of substantially normal size, with reflecting means for erecting the 75 image and for increasing and decreasing the distance which the light will travel in passing from the objective lens to the eye-piece, and an indicating means coöperating with a dioptric scale for indicating the nature of 80 the light rays emanating from the eye-piece.

4. In an ophthalmological instrument, the combination with an objective lens having a positive focal point, and an eye-piece also having a positive focal point substantially 85 the same as said objective lens, of reflecting means for erecting the image and for varying the distance of the light travel between said objective and said eye-piece, and means for determining the amount of said variations 90 in said distances in ophthalmic lens equivalents.

5. In an ophthalmological instrument, a support, a reflecting device carried thereby for directing light to the object, an objective 95 lens suitably supported with relation to said reflecting device, a reflector for said objective lens, a sight opening, a reflector for said sight opening, means for directing the light from one reflector to the other reflector, said means being adjustable with respect thereto, an ophthalmic lens-scale for determining the amount of adjustment of the light directing means, and a series of 100 lenses suitably mounted to be brought into alignment with said sight opening.

6. In an ophthalmoscope, a body portion, a source of light, a reflector adapted to direct light from said light source to the object, an objective lens and a reflector co-acting therewith, an eye lens and a reflector coacting therewith, an adjustable mounted reflector for focusing the instrument upon the object, and means for recording said adjustment in ophthalmic lens equivalents.

7. In an ophthalmoscope, a body portion, a source of light, a reflector adapted to direct light from said light source to the object, a lens and a reflector coacting therewith, a second lens and a reflector coacting therewith, a third reflector for directing the light from the first to the second mentioned reflector, and movable means carrying the third reflector for focusing the instrument for the correction of errors in the refraction of the observed eye, said means indicating substantially the required corrective lens values.

8. In an ophthalmoscope, a body portion, a source of light, a reflector adapted to di-

rect light from said light source to the object, a lens and a reflector coacting therewith, a second lens and a reflector coacting therewith, a third reflector for directing the light from the first to the second mentioned reflector, means movably supported by the body portion and carrying the third reflector for focusing the instrument, and means for indicating the amount of the focusing adjustment in ophthalmic lens values.

9. In an optical instrument, a support, a reflecting device carried thereby for directing light to the object, a light opening, a

reflector for the light opening, an eye-piece, 15 a reflector for said eye-piece, means for directing the light from one reflector to the other, said means being adjustable with respect thereto, an ophthalmic lens-scale for determining the amount of adjustment of 20 the light directing means, and a series of lenses suitably mounted to be brought into visual alinement with the instrument.
